(57) **CLAIM**

The ornamental design for a portable loudspeaker, substantially as shown and described.

DESCRIPTION

FIG. 1 is a front, bottom, left side perspective view of a portable loudspeaker;

FIG. 2 is a back, bottom, right side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken line portions of the drawings represent environmental structure only and form no part of the claimed design.
